FIG. 2. 3

Inventor:
L. A. Miller,
By George H. Christy
atty.

UNITED STATES PATENT OFFICE.

LEBBEUS A. MILLER, OF SEWICKLEY, PENNSYLVANIA.

BLOWER FOR STOVES AND FIRE-PLACES.

SPECIFICATION forming part of Letters Patent No. 317,404, dated May 5, 1885.

Application filed October 6, 1884. (No model.)

To all whom it may concern:

Be it known that I, LEBBEUS A. MILLER, a citizen of the United States, residing at Sewickley, in the county of Allegheny and State of Pennsylvania, have invented or discovered 5 certain new and useful Improvements in Blowers for Stoves and Fire-Places, of which improvements the following is a specification.

In the accompanying drawings, which make 10 part of this specification, Figure 1 is a front view, in elevation, of a stove embodying my improvements, and Fig. 2 a horizontal section through a portion of the front plate and one of the cover-plates, at the line *x x* of Fig. 1.

The object of my invention is to provide a 15 blower by the use of which the front of a stove or fire-place may be readily and conveniently opened and closed to a greater or less degree, as from time to time desired, for the purpose 20 of varying the draft of the fire and regulating the diffusion of heat therefrom in an apartment; and my improvements consist in a blower composed of a pair of vertically-sliding sections, coupled by flexible connections, and adapted to be moved simultaneously 25 in opposite directions and to cover or expose, either wholly or to any desired extent, the front opening of a stove or fire-place, and also in the combination, with a stove or fire-place, 30 of a pair of suspending-pulleys, journaled in side recesses in the front plate thereof, a pair of blower-sections fitting one above the other over an opening located in front of and above the fire-bed, and flexible connections passing 35 around the suspending-pulleys and coupled, at their opposite ends, to the upper and lower sections respectively. The improvements claimed are hereinafter fully set forth.

In the practice of my invention I form a 40 blower of two sections, 1 2, which are fitted to slide vertically in the front plate, 3, of a stove or fire-place, above the grate or fire-bed thereof, and over the opening in said front plate through which fuel is introduced, and 45 from which the heat of the fire is radiated into the apartment, said sections being adapted, by their movement towards or from each other, to close said opening, either entirely or to any partial extent, as may be desired. The sections 1 2 are located one above the other in the same vertical plane, the lower edge of the upper section, 1, abutting, when the sections

are closed together, against the upper edge of the lower section, 2, and they are made of substantially equal weight, so as to counterbalance each other and thereby to be susceptible of free vertical movement, which is imparted through a handle or handles, 4, secured to one or both of the sections. Mica lights or windows 5, fitted in each of the sections, permit 60 the illuminating effect of the fire to be exerted in an apartment when the blower is either wholly or partially closed.

The sections 1 2 are adapted to be moved coincidently in opposite directions by being 65 hung upon two suspending-pulleys, 6, journaled in the upper portions of side recesses, 7, formed in the front plate, 3. Chains 8, passing over the pulleys 6, are connected at their opposite ends to lugs or arms 9 10, 70 formed upon the sides of the upper and lower blower-sections 1 2, respectively, and the sections are thereby suspended on opposite sides so as to obviate tendency to cramping or tilting in their vertical movements, and their free 75 movement and retention in adjusted position are insured by being counterbalanced one by the other. Cover-plates 11, fitted over the side recesses, 7, serve to protect and conceal the suspending pulleys and chains. 80

The application of my improvements can be readily made to open-front stoves or grate fire-places of any of the ordinary constructions; and in the operation of my invention I avoid the inconvenience incident upon the use of a 85 removable blower, and enable the area of opening to be readily varied to increase or decrease draft, and regulate, as desired, the evolution of heat into the apartment. The blower-sections rest behind the front plate when 90 fully opened, offering no impediment to the discharge of heat or supplying of fuel, and when closed present a neat appearance and finish as part of the front, while by intermediate adjustments the degree of opening presented may be made to accord accurately 95 with the requirements of heating, and such opening is located in the most desirable position relatively to the fire-bed.

I claim herein as my invention—

1. The combination, in a blower for stoves or fire-places, of two sections coupled by flexible connections at their sides, said sections being adapted to fit one above another in a

vertical plane, and by their simultaneous movement in opposite directions to cover or to expose the entire or any desired portion of the area of front opening of a stove or fire-place, substantially as set forth.

5 2. The combination, with an open-front stove or fire-place, of a pair of suspending-pulleys journaled to the front plate on opposite sides thereof, a pair of blower-sections fitting one above the other over an opening in said front plate, and chains passing over said pulleys and connected at their opposite ends to the upper and the lower blower-sections respectively, substantially as set forth.

10 15 3. The combination of a stove or fire-place front plate having a central opening and a lateral recess on each side thereof, a pair of

suspending-pulleys journaled in said recesses, a pair of blower-sections fitting vertically one above the other over the opening of the front plate, and having lateral lugs or arms projecting into the recesses thereof, chains passing over the suspending-pulleys and connected at their ends to the lugs of the blower-sections, and cover-plates fitting over the lateral recesses and secured to the front plate, substantially as set forth. 20 25

In testimony whereof I have hereunto set my hand.

LEBBEUS A. MILLER.
